UNITED STATES PATENT OFFICE.

MELVIN L. STONE, OF WATERVILLE, MAINE, ASSIGNOR TO DRAPER COMPANY, OF HOPEDALE, MASSACHUSETTS, A CORPORATION OF MAINE.

WEFT-CARRIER CHUTE FOR AUTOMATIC WEFT-REPLENISHING LOOMS.

1,082,051.

Specification of Letters Patent. Patented Dec. 23, 1913.

Application filed July 17, 1911. Serial No. 638,880.

To all whom it may concern:

Be it known that I, MELVIN L. STONE, of Waterville, in the county of Kennebec, in the State of Maine, have invented a Weft-5 Carrier Chute for Automatic Weft-Replenishing Looms, of which the following is a specification.

In automatic weft-replenishing looms wherein the replenishment is effected by 10 ejecting the spent weft-carrier from the shuttle and inserting a fresh weft-carrier in its place, it is the usual practice to slot the lay beneath the shuttle box at the replenishing side of the loom for the downward es-15 cape of the spent weft-carriers, and the spent weft-carriers are received within a receptacle provided for that purpose. It occasionally happens with such looms that the ejected weft-carriers are so discharged that 20 they fail to fall into the receptacle and, accordingly, either drop to the floor or sometimes upon moving parts of the loom with the result that many of the weft-carriers are broken or injured. 25 The special object of the present invention is to furnish a weft-carrier chute intermediate between the lay and the receptacle so that the spent weft-carriers discharged from the shuttle shall with certainty be directed 30 into the receptacle.

The present invention is illustrated in the accompanying drawings, wherein—

Figure 1 is a front view of a portion of the loom at the replenishing side, illustrating the lay, the immediately associated portions of the weft-replenishing mechanism and the weft-carrier chute, and the upper part of the receptacle being shown in vertical longitudinal section. Fig. 2 is a detailed 40 section in the plane indicated by the line 2—2 in Fig. 3, and illustrates the yielding mounting of the rear plate of the weft-carrier chute. Fig. 3 is a vertical section through the lay and shuttle box at the re-45 plenishing side of the loom and through the receptacle and the intermediate weft-carrier chute, the immediately coöperating portions of the weft-replenishing mechanism being shown in side elevation, the section being in 50 the plane indicated by the line 3—3 in Fig. 1. Fig. 4 is a perspective view of the flexible front of the weft-carrier chute.

A is the lay, and B is the shuttle occupying the shuttle box at the replenishing end of 55 the lay. The lay is slotted at *a* for the down-

ward discharge of the weft-carriers of which one is shown at C within the shuttle. The spent weft-carrier is discharged simultaneously with the insertion of a fresh weft-carrier within the shuttle by means of a 60 transerrer D. The transerrer is given its transferring movement whenever the transerrer dog E is lifted into the path of the bunter F carried by the lay, this elevation of the transerrer dog being automatically 65 brought about whenever the condition of the weft in the loom demands replenishing. Fig. 3 shows the transerrer dog in uplifted position and moved forward by the lay bunter F. This figure shows the transerrer 70 in the position which it occupies just as it has transferred a fresh weft-carrier into the shuttle, and the ejected spent weft-carrier is shown at C at the bottom of the receiving can or receptacle G. In all of these respects 75 the construction, organization and mode of operation are substantially as commonly employed in the well-known Northrop loom as shown, for example, in United States Letters Patent No. 529,940, November 27, 1894. 80

The present invention resides in the chute which receives the spent weft-carriers as they fall from the shuttle through the lay slot *a* and which with certainty directs them into the receptacle G. This weft-carrier chute comprises two principal members, namely, a directing guide plate and a cover therefor. The directing guide plate is shown at H and it is inclined downwardly and forwardly from the lay to the mouth 90 of the receptacle G, as shown in Fig. 3. The transfer of weft-carriers occurs when the lay is at front center, as indicated in Fig. 3, and when the lay occupies this position the upper edge of the plate H is immediately 95 adjacent the rear wall of the lay slot *a*. Accordingly, when a weft-carrier is discharged from the shuttle it drops on to this guide plate and is directed thereby into the open mouth of the receptacle G. At each side of the guide plate are forwardly projecting guards I and J suitably arranged so as to prevent any endwise escape of the weft-carriers as they roll or slide down the plate H. The contour of the outer guard I is 105 shown in dotted lines in Fig. 3. It is important that this member of the chute comprising the parts H, I and J should be yieldingly mounted so that no damage will be 110 caused in case of any obstruction existing

between the lay and said member as, for example, may sometimes occur in case a fresh weft-carrier is improperly inserted within the shuttle or is prematurely discharged therefrom. Such a yielding mounting is shown in the drawings. As illustrated, these parts H, I and J are made of a single piece of sheet metal and are fastened to a hub K which turns on a stud L, carried by a fixed part of the loom frame. This hub is connected with a spring M surrounding the stud L and also connected to collar b fast on said stud. This spring normally retains the parts H, I and J in the position shown in Fig. 3, but permits their forward tilt in case of any blow at the rear.

The front member of the chute comprises a yielding apron N, made of leather, canvas or other stiff and durable, flexible material, and it is mounted upon the transferrer dog E, so as to rise and fall therewith. As illustrated, the upper edge of the apron is folded over a wire O and is secured thereto and this wire has an eye P at its inner end, through which passes a clamping bolt Q, which screws into the transferrer dog E and clamps the retaining wire O of the apron N thereto. The apron N hangs downwardly against the lower portion of the guide plate H and extends below the same, as shown in Figs. 1 and 3. From their line of contact the apron N and plate H diverge upwardly, thereby presenting an enlarged open mouth for the chute to receive the falling weft-carriers. The yielding apron constitutes the entire front wall of the guide chute.

During the normal running of the loom, the transferrer dog occupies a low position out of reach of the lay bunter F and the apron N is likewise then out of reach of the lay bunter, so that it is not struck thereby. When, however, the transferrer dog is elevated into the path of the lay bunter, the apron is likewise raised, thereby closing the front of the chute altogether, so that there is no possibility of a discharged weft-carrier escaping from the chute except at its bottom. When a weft-carrier is discharged it drops into the chute and in falling encounters the lower free portion of the yielding apron N and pushes it aside and then drops into the receptacle G. The apron N has the further office of retarding the descent of the weft-carrier so that it does not drop violently into the receptacle G. Both the apron N and the guide-plate yield forwardly, but the apron yields at each transfer, while the guide plate yields only in emergencies.

I claim:

1. An automatic weft-replenishing loom having, in combination, a slotted lay and a bunter thereon; weft-replenishing mechanism comprising a transferrer and a trans-

ferrer dog, which is moved into the path of the lay bunter when the weft requires replenishment; and a guide chute adapted to receive spent weft-carriers discharged through the slot of the lay, said chute comprising a downwardly and forwardly inclined guide plate with side flanges, said guide plate being yieldingly mounted so as to tilt forward should an emergency require, and a yielding flexible apron, supported by and moving with the transferrer dog, said apron constituting the front wall of said chute and bearing near its lower portion upon the guide plate, said apron and guide plate diverging upwardly from their place of contact. 70

2. An automatic weft-replenishing loom having, in combination, a slotted lay and a bunter thereon; weft-replenishing mechanism comprising a transferrer and a trans-ferrer dog, which is moved into the path of the lay bunter when the weft requires re-plenishment; and a guide chute adapted to receive spent weft-carriers discharged through the slot of the lay, said chute comprising a downwardly and forwardly inclined guide plate with side flanges, said apron constituting the front wall of said chute and bearing near its lower portion upon the guide plate, said apron and guide plate diverging upwardly from their place of contact. 85

3. An automatic weft-replenishing loom having, in combination, a slotted lay and a bunter thereon; weft-replenishing mechanism comprising a movable transferrer, and a guide chute adapted to receive spent weft-carriers discharged through the wall of the lay, said chute having an apron which is moved into position when the transferrer acts. 95

4. An automatic weft-replenishing loom having, in combination, a guide chute for receiving and conveying spent weft-carriers discharged from the loom, said guide chute comprising a yieldingly mounted inclined guide plate with side flanges, and a yielding apron in front of said guide plate, said guide plate and apron diverging upwardly to present a wide entrance mouth, and said apron being operatively mounted so as to be raised when a spent weft-carrier is to be received in the guide chute. 110

5. An automatic weft-replenishing loom having, in combination, a lay slotted for the discharge of spent weft-carriers, a guide chute with its mouth below the lay slot for receiving and conveying spent weft-carriers discharged from the lay, said guide chute comprising a yieldingly mounted inclined guide plate, and a yielding apron in front of said guide plate, said guide plate and apron diverging upwardly to present a wide entrance mouth, said apron being operatively 125

mounted so as to be raised when a spent weft-carrier is to be received in the guide chute, and being attached near its upper end with its lower end free, said lower free end 5 normally resting upon the lower end of the guide plate.

6. An automatic weft-replenishing loom having, in combination, a lay slotted for the discharge of spent weft-carriers, a guide chute with its mouth below the lay slot for receiving and conveying spent weft-carriers discharged from the lay, said guide chute comprising a yieldingly mounted inclined 10 guide plate, and a yielding apron in front of said guide plate, said guide plate and apron 15 diverging upwardly to present a wide entrance mouth, and said apron being attached near its upper end with its lower end free, said lower free end normally resting upon 20 the lower end of the guide plate.

7. An automatic weft-replenishing loom having, in combination, a lay slotted for the discharge of spent weft-carriers, a guide chute with its mouth below the lay slot for receiving and conveying spent weft-carriers discharged from the lay, said guide chute comprising an inclined guide plate, and a 25 yielding apron in front of said guide plate, said guide plate and apron diverging upwardly to present a wide entrance mouth, and said apron being attached near the upper end with its lower end free, said lower free end normally resting upon the lower 30 end of the guide plate.

8. An automatic weft-replenishing loom having, in combination, a lay slotted for the

discharge of spent weft-carriers, a guide chute with its mouth below the lay slot for receiving and conveying spent weft-carriers discharged from the lay, said guide chute 40 comprising a guide plate, and a yielding apron in front of said guide plate and attached near its upper end with its lower end free, said lower free end normally resting upon the lower end of the guide plate. 45

9. An automatic weft-replenishing loom having, in combination, a lay slotted for the discharge of spent weft-carriers, a guide chute with its mouth below the lay slot for receiving and conveying spent weft-carriers 50 discharged from the lay, said guide chute comprising a guide plate, and a yielding apron in front of said guide plate and attached near the upper end with its lower end 55 free.

10. An automatic weft-replenishing loom having, in combination, a lay slotted for the discharge of spent weft-carriers, a guide chute with its mouth below the lay slot for receiving and conveying spent weft-carriers 60 discharged from the lay, said guide chute comprising a guide plate and an apron in front of said guide plate and attached near the upper end with its lower end free. 65

In witness whereof, I have hereunto signed my name in the presence of two subscribing witnesses.

MELVIN L. STONE.
